UNITED STATES PATENT OFFICE.

JOHN D. HENDERSON, OF EVERETT, MASSACHUSETTS, ASSIGNOR TO HENDERSON TRAPO-CRETE COMPANY, OF BOSTON, MASSACHUSETTS, A CORPORATION OF MASSACHUSETTS.

CONSTRUCTING OR PAVING STREET, ROAD, AND OTHER WAYS.

No. 869,181.

Specification of Letters Patent.

Patented Oct. 22, 1907.

Application filed March 14, 1906. Serial No. 306,065.

To all whom it may concern:

Be it known that I, JOHN D. HENDERSON, a citizen of the United States, residing at the city of Everett, in the county of Middlesex and State of Massachusetts, 5 have invented new and useful Improvements in Constructing or Paving Street, Road, and other Ways, of which the following is a specification.

This invention in the construction, or building, or paving of street, or other road-ways,—the same having 10 been prepared or subgraded as ordinary, or well known or otherwise suitably,—consists in covering the subgraded, or prepared bed, with a layer or binder, one inch, or more or less, in thickness, (an inch being practically sufficient) consisting of clay and gravel, or hard 15 pan, as it is known, and over and on which is then placed a layer, four inches, more or less, in thickness, (four inches being practically sufficient) of crushed or broken stone, macadam, which is so rolled as to incorporate therewith the said binder and thereby produce of and 20 from the two a single, compact, close and hard layer, and then on this so combined layer, evenly disposing a layer of crushed or broken stone, two inches, or more or less in thickness, (two inches being practically sufficient), which said broken stone in its several particles 25 or pieces is such as would be gaged or determined by a ring or mesh of two and one half inches or thereabouts, and then coating in any suitable manner, this layer of broken stone with a liquid tar or other bituminous preparation and then disposing and finally working into 30 and filling the voids or interstices between and among the several particles or pieces of said upper strata or layer of broken stone, a bituminous or tar mixture together with small particles of stone, such, for instance, as what is commonly known as pea stone, all suitably 35 heated, which, in substance, completes the construction of the paving, or the street or other road-way in accordance with this invention and as will hereinafter more fully appear.

In the accompanying drawings, forming part of this 40 specification, the several figures 1 to 5, both inclusive, are similar vertical cross sections, from curb to curb, illustrating the construction of the paving, or road-way, at its various or successive steps or stages, and Figs. 6 and 7 are further views, as will hereinafter appear, on an enlarged scale compared with the preceding figures, for 45 the purpose of better illustration of the several steps in the construction of the pavement.

In the drawings, A and B are the two side curbs of the road-way.

50 C is the sub-graded bed.

D is the binder layer, which may be of any suitable material, and is sprinkled, or otherwise loosely disposed upon and over the bed C, to the thickness of an inch, or thereabouts.

E is a layer of crushed, or broken stone, or macadam, 55 as well known, on top of the binder layer D to the thickness of four inches, or thereabouts, and which is then rolled compactly and closely together forcing the same into the binder D, and the binder into and throughout the voids or spaces or crevices between the particles of 60 stone and making the whole, binder and stones, into a common layer, such substantially as shown, Fig. 3.

F is a layer of broken or crushed stone. The size of the several particles of this layer is determined by a ring or mesh of two and one half inches, or thereabouts, 65 as well known, and they are evenly spread or disposed over and upon the common layer before explained to the thickness of two inches, or thereabouts, leaving voids or crevices or open spaces between the particles, illustrated, Fig. 4. The upper surface of this layer F 70 is then evened off and covered with a liquid tar or bituminous preparation, and then the crevices or voids are filled with a tar, or other such like mixture combined with small stones, such as the well known pea stones, while the same is in a suitable heated condition, 75 and firmly compacted together by rolling, which completes the construction or pavement of the road-way, see Fig. 5, and in which the larger stones form the wearing surface of the pavement.

A pavement or road-way produced as above described 80 is most solid and compact, and its wearing and lasting qualities are most durable, efficient and desirable in every respect, and to the highest degree, as has been practically demonstrated. Furthermore it is most inexpensive in comparison with other well known road-ways or pavements.

With a view to more clearly illustrating my method; Fig. 6 shows perspectively the different stratas of material in the process of construction, while Fig. 7 on the right side clearly illustrates the way all parts are forced 90 toward and into each other, the pea stones in the top crevices or voids and the binding or hard pan when compressed, as in the finished roadway, the portion on the left being shown in a loose state to more clearly show the normal state of the material, provided I did 95 not choose to roll the layer of stone E previous to putting on the top F, or in the event of not putting the small pea stone on after the top layer had been rolled. The only reason for not allowing them to remain loosely in position until finally rolled is that by the layer of 100 stone E being rolled into the binding material a more compact foundation is secured for the layer F and by just smoothing this last course with the roller the voids are left sufficiently large to receive the coat of pea stone.

One object in having the proper proportion of the 105 material used, as hereinbefore stated, is with a view to allowing only enough of the lower binder which holds the stone E in place to fill all the voids from the under-

side, but after rolling will still leave the top of this layer E free and clean, ready for the layer F. After the top layer F is in place and rolled enough to give an even top, it is then ready to have the coated pea stone applied and as there is no foreign matter to prevent it having a free flow downward to the depth of the top of the layer E, the top and bottom becomes practically united in one mass, completing a solid thickness from sub-grade to surface.

10 Having thus described my invention what I claim and desire to secure by Letters Patent is,

A roadway constructed of a suitably prepared sub-graded foundation; a binder-layer composed of clay and gravel or hard-pum one inch or so in thickness on said foundation; 15 a layer composed of broken or crushed stone or macadam

four inches or so in thickness on, and rolled or otherwise suitably worked into and intermingled with said binder-layer; a layer composed of broken and crushed stone the pieces of which are two and one half inches or so in size evenly disposed on said intermingled layers, and a layer composed of a mixture of pea or other such like small stones and tar or bitumen, both of which before being mixed and laid have been heated, and that is rolled or otherwise suitably worked into and made to fill the voids between the pieces of said broken or crushed stone and to 20 present and to constitute such stones as the wearing surface of the roadway, all substantially as described.

In witness whereof, I have hereunto set my hand in the presence of two subscribing witnesses.

JOHN D. HENDERSON.
